CLAIM

The ornamental design for a combined ceiling fan mounting canopy, downrod, motor housing, switch housing, blade irons and light fixture unit, as shown and described.

DESCRIPTION

FIG. 1 is a front-bottom perspective view of a combined ceiling fan mounting canopy, downrod, motor housing, switch housing, blade irons and light fixture unit showing my new design;

FIG. 2 is a front elevational view thereof;

FIG. 3 is a rear elevational view thereof;

FIG. 4 is a left elevational view thereof; and

FIG. 5 is a right elevational view thereof;

FIG. 6 is a top plan view thereof; and

FIG. 7 is a bottom plan view thereof; and,

FIG. 8 is a perspective view thereof;

The broken line showing of environmental structure in FIG. 8 is for illustrative purposes only and forms no part of the claimed design.
